WILHELM F. JAENECKE, OF NORTH TONAWANDA, NEW YORK, ASSIGNOR TO ALLAN HERSCHELL COMPANY, INC., OF NORTH TONAWANDA, NEW YORK, A CORPORATION OF NEW YORK.

ANIMAL-MOUNT FOR CAROUSELS.

1,186,659.

Specification of Letters Patent. Patented June 13, 1916.

Application filed January 5, 1916. Serial No. 70,521.

To all whom it may concern:

Be it known that I, WILHELM F. JAENECKE, a citizen of the United States, residing at North Tonawanda, in the county of 5 Niagara and State of New York, have invented a new and useful Animal-Mount for Carousels, of which the following is a specification.

The present invention relates to an improved mounting for the animal, or other figure, which is used on carousels, and has for an object to provide a connection or mounting which may be quickly assembled and quickly separated, and which when assembled provides for an interlocked joint, which cannot be accidentally released, and which admits of the noiseless rocking or oscillating movement of the parts, as the animal is moved back and forth in the usual 20 manner.

The invention has for another object the provision of a mounting of this character between the standard which carries the animal, or other figure, and the platform, so as 25 to anchor the standard to the platform, and at the same time admit of the free vertical movement of the standard, and the free rocking or oscillation of the standard without undue wear upon the parts and without 30 liability of disconnecting the same.

A further object of the invention is to provide a connection, the parts of which are not only housed, but are also completely covered, and which are of such peculiar 35 form and arrangement as to admit of the formation thereof of considerable thickness, and size, to amply hold the animal, or other figure, from accidental displacement during the operation of the carousel.

40 Other objects and advantages of this invention will be more particularly pointed out in the following specific description of the present preferred embodiment of this invention, the same being disclosed in the 45 accompanying drawing, wherein:

Figure 1 is a vertical central sectional view, taken through the lower end of a standard, and the improved mount or connection between the standard and the platform, the lower side of the animal or figure being shown fragmentarily in its relative position on the standard. Fig. 2 is a central sectional view, taken through the mount or connection of this invention, at right angles 50 to the showing in Fig. 1, parts of the con-

nection being shown in elevation. Fig. 3 is a transverse section through the mount or connection, taken on the line 3—3 of Fig. 1, and looking downwardly in the direction of the arrow, the dotted lines showing the contour and position of the base plate beneath the platform. Fig. 4 is a detail sectional view through the socket ring, showing in elevation one of the trunnion lugs projecting from the inner wall of the socket ring. Fig. 65 5 is a detail vertical sectional view, taken through the connecting nipple, showing the vertical slots formed in the lower flange of the nipple.

Referring to this drawing, wherein like parts are designated by similar characters of reference throughout the several views, 10 designates the animal, or other figure, which is supported by the improved mount or connection of this invention. The figure 10 is 75 secured to an outer tubing 11 into which telescopes an inner tube 12. The lower end of the standard thus formed is protected or incased in a cylindrical casing 13, which incloses the lower extremity of the outer 80 tube 11 to prevent contact of clothing, hands, and the like, with the movable tube.

The platform 14 of the carousel is provided immediately beneath the figure 10 with an opening through which upwardly 85 extends a socket ring 15 held from upward displacement by a base flange 16 adapted to seat flat against the lower side of the platform 14. The base flange 16 is secured to the platform in any suitable manner, such 90 as by bolts 17 countersunk in the upper face of the platform and extending downwardly through the base plate. This socket ring 15, as may be best seen from Figs. 1, 3 and 4, is provided, in its diametrically opposite 95 sides, with inwardly extending lugs 18 having lower rounded or semi-cylindrical faces constituting trunnions or journals. A cap plate 19 is provided with an outstanding flange 20 adapted to seat against the lower 10 edge of the socket ring 15 and is seated in a depression 21 formed in the lower face of the base flange 16, so as to center the cap 19 beneath the socket ring 15, and hold the cap in place. The cap 19 carries therein a coiled spring 22 resting at one end in the bottom of the cap 19 and bearing at its upper end against a follower plate 23, in the

form of a washer, which is free to move vertically in the socket ring 15, and which

is also capable of a slight oscillation in the ring. To prevent the binding of the parts under the compression of air in the mount or connection, the cap plate 19 is provided in its bottom, with an opening 24, and the follower plate 23 is provided at its central portion with an opening 25. Screws 26, or the like, pass upwardly through the flange 20 and into the base plate 16 to hold the cap plate 19 against the socket ring 15.

A connecting nipple 27 is internally threaded at its upper end to receive therein the lower externally threaded extremity of the telescoping tube 12 of the standard. The upper end of the nipple 27 is the larger end thereof, and is provided with a smooth cylindrical peripheral surface, and has formed thereon at the lower end of the surface an outstanding bead or flange 28 constituting a supporting shoulder upon which seats the lower end of the cylindrical casting 13, which latter also snugly embraces the periphery of the upper end of the nipple 27. The lower end of the nipple 27 is reduced for passage into the upper end of the socket ring 15, between the lug trunnions 18. The lower end of the nipple has an outstanding annular flange 29, of a diameter to somewhat closely fit the interior of the socket ring 15. This flange 29 has, at diametrically opposed points, vertical slots 30 extending therefrom and being of a width to receive the lug trunnions 18 therethrough as the lower end of the nipple is inserted into the top of the socket ring 15. At points intermediate the slots 30, the flange 29 is provided with diametrically opposed concavities or recesses 31 in the upper face of the flange. The bottoms of the recesses 31 extend down to a point substantially half the thickness of the flange, so as to provide for ample support at the bottom of the recess for anchoring the nipple in the socket ring. These recesses 31 are adapted to receive therein the lower cylindrical portions of the trunnions 18, and, as shown in Fig. 2, the recesses 31 are so dished out or concaved as to loosely receive the trunnions 18 therein, and admit of the free rocking of the flange upon the trunnions as a pivotal support. The follower plate 23 bears against the lower end of the nipple 27, and the spring 22 is of such strength or tension as to force the nipple 27 upwardly and hold the flange 29 against the trunnions 18 and prevent the accidental dislodgment of the standard from the platform.

In assembling the parts, it is only necessary to turn the nipple 27 until the slots 30 in the flange 29 register with the lug trunnions 18 projecting inwardly from the wall of the socket ring 15. The follower plate 23 bears against the lower sides of the trunnions 18 when the nipple is removed from the socket, so that the spring and its

follower cannot be accidentally dislodged from the socket. The nipple, when the slots are so adjusted, is forced downwardly into contact with the follower plate 23, and against the tension of the spring, until the flange 29 clears the lug trunnions 18. While in this depressed position, the nipple 27 is given a turn through substantially 90°, to register the concavities or recesses 31 in the flange 29 with the lug trunnions 18. The nipple 27 is now released when the spring 22 forces the nipple upwardly and seats the trunnions 18 in the recesses 31. A rocking movement of the animal, or other device 10, mounted on the standard is permitted as the nipple 27 pivots upon the trunnions 18, and the outer tube 11 is permitted to slide vertically upon the inner tube 12. Thus, a noiseless rocking connection is formed for the lower end of the standard, and a construction is provided which admits of the quick separation of the parts, and which at the same time, when assembled, securely holds the parts in interlocked relation.

It is, of course, understood that various changes and modifications may be made in the details of the above described construction, without departing from the spirit of the invention, and being restricted only by the scope of the following claims.

What is claimed is:—

1. In combination with a standard, a protecting casing surrounding the standard, and a platform, a socket ring seated in the platform and having opposed inwardly extending lug trunnions, a spring in the lower end of said socket ring, and a nipple secured to the lower end of said standard and adapted to support the lower end of said casing, said nipple being reduced at its lower end for engagement in the upper end of said socket ring between said trunnions and having an annular flange provided with vertical slots adapted to register with the trunnions to admit the insertion of the nipple in the socket ring, said flange of the nipple also having concaved recesses in its upper face adapted to register with the trunnions upon the partial rotation of the nipple, said spring being adapted to raise said nipple to seat said trunnions in said recesses.

2. An animal mount for carousels, comprising an outer tube adapted for securement to the animal, a telescoping tube projecting below the end of the outer tube and being externally threaded at its lower end, a nipple having internal threads at its upper end secured upon the lower end of the telescoping tube, said nipple having a smooth cylindrical outer surface at its upper end, a casing engaging about the lower end of said tubes and fitting snugly over the upper end of said nipple, said nipple having an annular bead at the lower end of said smooth surface to receive and support the lower end of

said casing, a socket adapted for securement to the platform of a carousel and adapted to receive in its upper end the lower end of said nipple, opposed trunnions carried in the upper end of the socket, an outstanding flange carried upon the lower end of the nipple and having slots therein for the reception of said trunnions during the insertion of the nipple in the socket, said flange having concaved recesses in its upper face adapted to register with said trunnions upon the partial rotation of the nipple in the socket, and means urging the nipple upwardly in the socket for holding the trunnions in said recesses and adapted to admit the free rocking movement of the nipple in the socket.

3. An animal mount for carousels including a socket ring for engagement upwardly through the platform of a carousel and having a base plate adapted for securement against the under side of the platform, said socket ring having inwardly extending lugs provided with semi-cylindrical lower faces, 25 a cap plate secured to the lower edge of said socket bearing, an expanding spring seated in the cap plate, a follower plate movable in the socket ring and receiving the upper end of said spring thereagainst, a nipple adapted for securement to the standard of a carousel and having an annular flange thereon for engagement in the upper end of the socket ring, said flange having vertical slots therein for the passage of said lugs 30 therethrough, and having bearing faces at its upper side to register with said lugs upon the partial turning of the nipple in the

socket, said follower being adapted to bear against the lower end of said nipple to force the same upwardly and engage the bearing 40 faces against the lower rounded faces of said lugs.

4. In an animal mount for carousels, a socket member adapted for securement to the platform of a carousel, and having integral inwardly extending trunnions at its upper end, a nipple for securement to the lower end of the standard of a carousel adapted for engagement in said socket past said trunnions and having bearing faces 45 adapted to register beneath the trunnions upon the partial rotation of said nipple, and a spring seated in the socket for engagement with the nipple to urge the same upwardly and engage said bearing surfaces against 50 the trunnions to secure the nipple in the socket and admit of the rocking of the nipple with the standard.

5. In an animal mount for carousels, a fixed socket having opposed inwardly extending lugs, a nipple for insertion in the socket and having an outstanding flange for engagement beneath said lugs, and a spring pressed follower closing the upper end of the socket and adapted to bear against the nipple to force the same upwardly and hold the flange against the lugs.

In testimony, that I claim the foregoing as my own, I have hereto affixed my signature in the presence of two witnesses.

WILHELM F. JAENECKE.
